ATTORNEYS

UNITED STATES PATENT OFFICE.

WILTON F. JENKINS, OF RICHMOND, VIRGINIA.

TEMPERATURE-INDICATOR FOR AUTOMOBILE-RADIATORS.

1,340,830.

Specification of Letters Patent. Patented May 18, 1920.

Application filed May 3, 1919. Serial No. 294,536.

To all whom it may concern:

Be it known that I, WILTON F. JENKINS, a citizen of the United States, and a resident of Richmond, in the county of Henrico and the State of Virginia, have invented certain new and useful Improvements in Temperature-Indicators for Automobile-Radiators, of which the following is a specification.

This invention is an improved temperature indicator for automobile radiators.

One of the principal objects of the invention is to provide an indicator which will exhibit a column of steam to the driver of the automobile immediately the radiator begins to boil.

Another object of the invention is to provide a radiator cap with means whereby a column of steam will be exhibited as soon as the radiator begins to boil, so that the driver will be informed either in the daytime or at night of the fact that the water is boiling.

A further object of the invention is to provide an improved temperature indicator of the class described which will be exceedingly simple, durable, efficient in operation and inexpensive to manufacture and maintain.

With these and other objects in view, which will become apparent as the description proceeds, the invention resides in the construction, combination and arrangement of parts hereinafter more fully described and claimed, and illustrated in the accompanying drawing in which like characters of reference indicate like parts throughout the several figures of which:

Figure 1 represents a perspective view of the radiator of an automobile equipped with an automobile temperature indicator constructed according to my invention.

Fig. 2 represents a vertical section view of the invention.

Referring more particularly to the drawing; I provide a radiator cap 5 with a central opening 6 through which an exteriorly threaded tube 7 is passed. This tube is enlarged at its lower end as at 8 to provide a shoulder 9 engaging against the under face of the cap 5. The bore 10 of the tube is branched as at 11 at a point below the shoulder 9, and the enlarged end 8 of the tube, below the branches 11, is provided with a circular baffle plate 12.

55 A cap tube 13 inferiorly threaded at its

lower end as at 14, is screwed onto the upper end of the tube 7, and carries the washer 15 forming a tight fit between the tube and the radiator cap. The upper end of the cap tube is provided with a restricted port 16 of a diameter less than the diameter of the bore 10 of the tube 7.

In operation, as soon as the water begins to boil, the steam will pass up through the annular space between the baffle plate and the interior of the radiator cap, and will find its way through the branches 11 and the bore of the tube 7, into the cap tube 13 and out in the form of a column through the restricted port 16. By reason of the fact that the port 16 is of a relatively small area as compared with the bore of the tube 7, the pressure within the tube 13 will be built up sufficiently to eject the steam in a column up through the port 16. This column of steam will immediately notify the driver, in the daytime, or at night, of the fact that the water is boiling. It will be exhibited at night by reason of the fact that the column will show up clearly against the rays from the head lights.

The baffle plate 12, while allowing a ready passage of steam through the tubes, will prevent water from being splashed up through the branches 11 into the tubes.

The portion 18 of enlarged end 8 of the tube, below the baffle plate 12 is preferably polygonal in conformation so as to form a nut for receiving a wrench in assisting the assembly of the device. Similarly the cap tube may be made polygonal in form at a suitable point as at 19.

Although I have described the preferred embodiment of my invention, I may desire to make such changes in the construction, combination and arrangement of parts thereof as do not depart from the spirit of the invention and the scope of the appended claims.

I claim:

1. The combination with a radiator cap, of a tube extending therethrough and having an enlarged lower end providing a shoulder engaging against the under surface of the cap, the bore of the tube being branched at a point below the shoulder, a baffle plate arranged below the branches of the bore for preventing water being splashed into the tube and a cap tube arranged on the upper side of the radiator cap and engaging the

first said tube and provided with a restricted port of a diameter less than the diameter of the first said tube.

2. The combination with a radiator cap 5 of a tube extending therethrough and having an opening at its inner end at a point below the surface of the radiator cap, a baffle plate carried by the tube below and extending laterally beyond the opening 10 thereof, and a cap tube arranged on the radiator cap engaging the first said tube and provided with a restricted port.

3. The combination with a radiator cap, 15 of a tube extending therethrough, the bore of the tube being provided at its lower end

with lateral branches opening within the cap, an outwardly extending baffle plate carried by the tube below said branches, and a cap tube arranged on the radiator cap and engaging said first named tube, said cap 20 tube being provided with a small port.

4. The combination with a radiator cap, of a tube extending therethrough and having a bore terminating at its lower end in lateral branches opening within the cap, an 25 outwardly extending baffle plate formed integrally upon said tube below said branches, and a cap tube on the upper end of said first named tube provided with a port.

WILTON F. JENKINS.
